COMMUNICATING FLUIDS WITH A
HEATED-FLUID GENERATION SYSTEM

TECHNICAL FIELD

This document relates to a tube system for use in a wellbore, such as for use in the delivery of fluids to a downhole heated-fluid generator device.

BACKGROUND

Fluids in hydrocarbon formations may be accessed via wellbores that extend down into the ground toward the targeted formations. In some cases, the hydrocarbon formations may have a lower viscosity such that crude oil flows from the formation, through production tubing, and toward the production equipment at the ground surface. Some hydrocarbon formations comprise fluids having a higher viscosity, which may not freely flow from the formation and through the production tubing. These high viscosity fluids in the hydrocarbon formations are occasionally referred to as "heavy oil deposits." In the past, the high viscosity fluids in the hydrocarbon formations remained untapped due to the inability and expense of recovering them. More recently, as the demand for crude oil has increased, the commercial operations have expanded to the recovery of such heavy oil deposits.

In some circumstances, the application of heated fluids (e.g., steam) to the hydrocarbon formation may reduce the viscosity of the fluids in the formation so as to permit the extraction of crude oil and other liquids from the formation. The design of systems to deliver the steam to the hydrocarbon formations may be affected by a number of factors.

One such factor is the location of the steam generators. If the steam generator is located above the ground surface, steam boilers may be used to create the steam while a long tube extends therefrom to deliver the steam down the wellbore to the targeted formation. Because a substantial portion of the heat energy from the steam may be dissipated as the steam is transported down the wellbore, the requisite energy to generate the steam may be costly and the overall system can be inefficient. If, in the alternative, the steam generators are located downhole (e.g., in the wellbore below the ground surface), the heat energy from the steam may be more efficiently transferred to the hydrocarbon formation, but the amount of heat and steam generated by the downhole device may be limited by the size and orientation of the downhole steam generator and by constraints on the supply of water and fuels. Furthermore, installation of the downhole steam generators, including the attachment of supply tubes that provide water, air, fuel, or the like from the ground surface, may be complex and time consuming.

SUMMARY

Some embodiments of a supply tube system for use in a wellbore may have multiple tubes—a number of which can be readily coupled to a downhole steam generator or other heated-fluid generator device. In certain embodiments, the system may include a connector that simplifies the process of coupling the supply tube system to the steam generator and provides for fluid communication between each supply conduit and the associated input port of the steam generator.

One aspect encompasses a method in which a heated-fluid generator device is lowered into a wellbore coupled to a first tube. The first tube supports at least a portion of a weight of the heated-fluid generator device while lowering the heated-fluid generator device into the wellbore. A second tube is

2

coupled to the heated-fluid generator. One of the first and second tubes is disposed inside of the other tube to define a first fluid conduit inside of a second fluid conduit. At least one of the first tube and the second tube comprises a coiled tubing uncoiled from a spool and inserted into the wellbore.

Another aspect encompasses a method in which a heated-fluid generator device is lowered into a wellbore coupled to a first tube. The first tube supports at least a portion of a weight of the heated-fluid generator device while it is being lowered into the wellbore. The first tube is uncoiled from a spool as the heated-fluid generator device is lowered into the wellbore. A second tube is coupled to the heated-fluid generator such that one of the first and second tubes is nested within the other to define at least a portion of at least two fluid conduits.

Another aspect encompasses a system for generating heated fluid in a wellbore. The system includes a heated-fluid generator device disposed in a wellbore and adapted to output a heated fluid. A first and second tubes reside in the wellbore and are coupled to the heated-fluid generator. The first tube resides within the second tube so as to define a inner fluid conduit disposed within an intermediate fluid conduit. Both the inner and intermediate conduits are in fluid communication with the heated-fluid generator device. At least one of the first and second tubes comprises a coiled tubing.

These and other embodiments may be configured to provide one or more of the following advantages. First, the supply tube system may efficiently use the space within the wellbore to deliver fluids, such as water, air, and fuel, to the downhole heated-fluid generator device. For example, the supply tube system may comprise a plurality conduits that are substantially coaxial to one another—with the outermost conduit being at least partially defined by the wellbore casing. In such circumstances, the space within the wellbore may be efficiently used to deliver the fluids to the heated-fluid generator device. Second, the supply tube system may be partially coupled to the heated-fluid generator device before it is lowered into the wellbore. For example, at least one tube of the supply tube system may be coupled to the heated-fluid generator device above the surface while another tube is subsequently coupled to the heated-fluid generator device after it has been lowered into the wellbore. In such circumstances, the supply tube system may be readily coupled to the heated-fluid generator device and may facilitate the process of lowering the heated-fluid generator device into the wellbore. One or more of these and other advantages may be provided by the devices and methods described herein.

The details of one or more embodiments of the invention are set forth in the accompanying drawings and the description below. Other features, objects, and advantages of the invention will be apparent from the description and drawings, and from the claims.

DESCRIPTION OF DRAWINGS

FIG. 1 is a side view of an embodiment of a supply tube system and a heated-fluid generator device in a well.

FIG. 2 is a cross-sectional view of a portion of the supply tube system of FIG. 1 taken along line 2-2.

FIG. 3 is a cross-section view of the supply tube system of FIG. 1 within the wellbore taken along line 3-3.

FIG. 4 a diagram showing an embodiment of a process for deploying a supply tube system and a heated-fluid generator device in a wellbore.

Like reference symbols in the various drawings indicate like elements.

DETAILED DESCRIPTION OF ILLUSTRATIVE EMBODIMENTS

Referring to FIG. 1, a well 100 may include a well head 120 that is disposed proximal to a ground surface 150 and a wellbore 160. The well head 120 may be coupled to a casing 110 that extends a substantial portion of the length of the wellbore 160 from about the ground surface 150 towards a formation 130 (e.g., hydrocarbon-containing reservoir). In this embodiment the wellbore 160 extends in a substantially vertical direction toward the formation 130. It should be understood that, in other embodiments, at least a portion of the wellbore 160 may be curved or extend in a slanted or substantially horizontal direction. In some instances, the wellbore 160 may be formed by drilling from the surface 150 into the formation 130 and then lining the hole with the casing 110.

In some instances, some or all of the casing 110 may be affixed to the adjacent ground material with a cement jacket 170 or the like. The casing 110 may comprise metallic material. The casing 110 may be configured to carry a fluid, such as air, water, natural gas, or to carry an electrical line, tubular string, or other device. In some embodiments, the well 100 may be completed with the casing 110 extending to a predetermined depth proximal to the formation 130. A locating or pack-off device such as a liner hanger 400 (when deployed in the wellbore 160) can grip and, in some instances, substantially seal about the end of the casing 110. In such circumstances, a heated-fluid generator device 200 may be deployed so that the heated-fluid generator device 200 outputs heated fluid through an apertured liner 210 coupled to the liner hanger 400. The output heated fluid is thus exposed to the hydrocarbon producing formation proximal to the formation 130.

Still referring to FIG. 1, a heated-fluid generator device 200 may be at least partially disposed in the wellbore 160 proximal to the formation 130. The heated-fluid generator device 200 may be a device adapted to receive and heat an injection fluid. In one instance, the injection fluid includes water and the water may be heated to generate steam. The injection fluid can include other different fluids, in addition to or in lieu of water, and the injection fluid need not be heated to a vapor state (e.g. steam). The heated-fluid generator device 200 includes inputs to receive the injection fluid and other fluids (e.g., air, fuel such as natural gas, or both) and may have one of a number of configurations to deliver heated injection fluids to the formation 130. The heated-fluid generator device 200 may use fluids, such as air and natural gas, in a combustion or catalyzing process to heat the injection fluid (e.g., heat water into steam) that is applied to the formation 130. In some circumstances, the formation 130 may include high viscosity fluids, such as heavy oil deposits or the like. The heated-fluid generator device 200 may supply steam or another heated injection fluid to the formation 130, which may penetrate into the formation 130, for example, through fractures 133 in the formation 130. The application of a heated injection fluid to the formation 130 may reduce the viscosity of the fluids in the formation 130. In such embodiments, the fluids in the formation 130 may be more readily recovered by equipment at the ground surface 150.

In some instances, the formation 130 may be an injection formation in proximity of a producing formation, whereas the heated fluid injected into the formation 130 flows from the injection formation towards the producing formation, or

through a combination of conduction and convection heats the fluids in the producing formation. The producing formation is intersected by a separate producing wellbore. The heated fluid reduces the viscosity of the hydrocarbon fluids in the producing formation, thus increasing the flowrate of the hydrocarbon fluids from the producing formation into the producing wellbore. In some instances the injection formation is above the producing formation, whereas gravity assists in bringing the heated injected fluid in contact with the producing formation. This configuration is often referred to as steam assisted gravity drainage (SAGD).

The heated-fluid generator device 200 may be in fluid communication with a supply tube system 140 having one or more supply tubes. As described in more detail below in connection with FIG. 2, the supply tubes may provide fluids or other items via conduits to the heated-fluid generator device 200. In some embodiments, a connector 500 may be used to join the supply tube system 140 to the heated-fluid generator device 200. Alternatively, the connector 500 may be integral with the heated-fluid generator device 200 so that the heated-fluid generator device 200 has the proper structure to directly engage one or more of the supply tubes.

Still referring to FIG. 1, the heated-fluid generator device 200 may be positioned in the wellbore 160 using a locating or pack-off device such as liner hanger 400. The liner hanger 400 may include an elongated cylindrical body 410 and slips 430. When the liner hanger 400 is actuated, the slips 430 are shifted to contact and grip the inner cylindrical wall of the casing 110. The slips 430 may retain the position of the liner hanger 400, which in turn retains the heated-fluid generator device 200 in the desired position proximal to the formation 130. In certain embodiments, the liner hanger 400 further includes substantially circumferential packer seals 420. The packer seals 420, when actuated, extend radially to press against and substantially seal with the casing. The liner hanger 400 may include a polished bore receptacle 450, which can be used to locate and retain the connector 500, the heated-fluid generator device 200, or both.

Referring to FIG. 2, the supply tube system 140 may include one or more tubes that are in communication with the heated-fluid generator device 200. In this embodiment, the supply tube system 140 includes the casing 110, an intermediate tube 610 and an inner tube 710. Other embodiments may include fewer or more tubes or may exclude the casing 110 as part of the supply tube system 140. In certain embodiments, some or all of the tubes of supply tube system 140 can be coupled to the heated-fluid generator device 200 using a connector 500. In some embodiments, each of these tubes 110, 610, and 710 of the supply tube system 140 may be disposed nested within one another. In some embodiments, they may be substantially coaxial relative to one another. Accordingly, tubes 110, 610, and 710 may be substantially concentric. In other embodiments, a longitudinal axis of one or more of the tubes 110, 610, 710 may be laterally offset from another of the tubes 110, 610, 710, but still nested.

The intermediate tube 610 and inner tube 710 of the supply tube system 140 may comprise a metallic or other material. If used in supporting the heated-fluid generator 200 as it is deployed into or out of the wellbore 160, the material may have sufficient strength to support the heated-fluid generator device 200. The intermediate tube 610 and inner tube 710 may be configured to carry a fluid, such as air, water, or natural gas. In some instances, the intermediate tube 610 and/or the inner tube 710 may comprise coiled tubing, a tubing that is provided to the well site coiled on a spool and uncoiled prior to or as it is deployed into the wellbore 160 (refer, for example, to FIG. 1 which shows a spool 145 of

coiled tubing that is uncoiled as it is lowered into the wellbore **160**). Suitable coiled tubing is available from Quality Tubing, Inc., of Houston, Tex., and from other coiled tubing manufacturers or suppliers. Coiled tubing is typically continuous with no readily separable connections (i.e. no threaded pin and box connections). However, it is within the scope of the invention to provide the coiled tubing with readily separable connections, such as ferrule type connections, bayonet style connections or with more permanent connections, such as welds or stab in permanent connections. Use of coiled tubing enables the tubing and any equipment attached to the tubing to quickly run into and out of the wellbore **160**, because it reduces or eliminates (if continuous) time spent connecting lengths of jointed tubing.

If not coiled tubing, the intermediate tube **610** and/or inner tube **710** may comprise other types of tubulars. For example, the intermediate tube **610** and/or inner tube **710** may comprise a string of consecutive jointed tubes that are attached end-to-end. Such a string of tubes may be used, for example, in embodiments that require tube walls having a thickness or diameter that would render providing the coiled tubing as undesirable, impractical, or impossible. The intermediate tube **610** and/or inner tube **710** may comprise helically wound steel tube umbilical or electrohydraulic umbilical tubing. The umbilical tubing can be provided with metallic wire, fiber optic, and/or hydraulic control lines, for example, for conveying power or signals between the heated-fluid generator **200** and the surface. Also, the intermediate tube **610** and inner tube **710** can be different types of tubes. For example, in one instance, the larger diameter intermediate tube **610** may be jointed tubing, while the inner tube **710** is coiled or umbilical tube.

In this embodiment, the intermediate tube **610** passes through an interior of the casing **110** and the resulting annulus between the casing **110** and the intermediate tube **610** at least partially defines an outer conduit **115**. When the intermediate tube **610** is secured to the connector **500**, the outer conduit **115** may be in fluid communication with ports **560** of the connector **500** (described in more detail below in connection with FIG. 3). As such, a fluid may be supplied from the outer conduit **115**, through the outer ports **560**, and to the corresponding input of the heated-fluid generator device **200**.

In this embodiment, the inner tube **710** passes through an interior of the intermediate tube **610** and the resulting annulus between the inner tube **710** and the intermediate tube **610** at least partially defines an intermediate conduit **615**. The inner tube **710** defines an inner conduit **715** therein. As such, the outer conduit **115** may have an annular configuration that surrounds the intermediate conduit **615**, and the intermediate conduit **615** may have an annular configuration that surrounds the inner conduit **715**.

Electric or hydraulic control lines may be disposed within one of the conduits, such as the inner conduit **715**, intermediate conduit **615** or the outer conduit **115**. For example, the electric or hydraulic control lines may be disposed in the conduit **115**, **615**, or **715** that passes air or other oxygenated gas to the heated-fluid generator **200**. The electric or hydraulic control lines may be capable of conveying power or signals between the heated-fluid generator **200** and other equipment on the surface **150**.

One or more of the supply tubes **610**, **710** may comprise centralizers that are adapted to maintain the tubes in a substantially coaxial position. The centralizers may comprise spacers that extend in a radial direction so as to maintain proper spacing between the tubes. Alternatively, one or more tubes may be self-centralizing when the tubes are coupled to

the heated-fluid generator device **200** inside the wellbore (described in more detail below).

While the intermediate tube **610**, inner tube **710**, connector **500** and/or heated-fluid generator device **200** can be assembled to one another in any order, on the surface or in the wellbore, in some embodiments the intermediate tube **610**, connector **500**, and heated-fluid generator device **200** may be assembled at the surface before being lowered into the wellbore **160**. The intermediate tube **610** may include threads **622** or another mechanical engagement device adapted to seal and secure the intermediate tube **610** with connector **500**. When the intermediate tube **610** is secured to the connector **500**, the intermediate conduit **615** may be in fluid communication with ports **570** of the connector **500**. As such, fluid may be supplied from the intermediate conduit **615**, through the intermediate ports **570** and to the corresponding input of the heated-fluid generator device **200**.

A stinger/seal assembly **720** may be disposed at the lower end of the inner tube **710** so that the inner tube may be readily connected with the connector **500** downhole. For example, the inner tube **710** with the stinger/seal **720** assembly may be lowered into the wellbore **160** inside of the intermediate tube **610** until a stab portion **722** of the stinger/seal assembly **720** engages an inner receptacle **522** of the connector **500**. In such circumstances a latch mechanism **730** of the stinger/seal assembly **720**, for example outwardly biased or adjustable dogs, may join with a mating groove **524** in the receptacle **522** so as to secure the position of the inner tube **710** relative to the connector **500**. In this embodiment, stinger/seal assembly **720** may include a seal **740** that substantially seals against the wall of the connector **500** to prevent fluid in the inner conduit **715** from seeping past the stinger/seal assembly **720** into the intermediate conduit **615**. When the inner tube **710** is joined with the connector **500**, the wall of the inner tube **710** may act as a divider, thus providing two distinct fluid paths (e.g., the inner conduit **715** and the intermediate conduit **615**) inside the intermediate tube **610**. The inner conduit **715** may be substantially cylindrical and in fluid communication with an inner port **580** of the connector **500**. As such, fluid may be supplied from the inner conduit **715**, through the inner port **580** and to the input of the heated-fluid generator device **200**.

As previously described, the connector **500** joins the heated-fluid generator device **200** to the supply tube system **140**. The connector **500** may have a circumferential seal **510** that substantially seals against the polished bore receptacle **450** to prevent fluid from seeping between the outer surface of the connector **500** and the receptacle **450**. In some circumstances, the seal **510** may be configured to maintain the seal between the surfaces at high operating temperatures. Furthermore, the connector **500** may include threads **440** or another mechanical engagement device to couple with the heated-fluid generator device **200**. As such, the connector may be coupled to the heated-fluid generator device **200** at the surface and then collectively lowered into the well as the threads **440** secure the heated-fluid generator device **200** to the connector **500**.

Still referring to FIG. 2, the connector may also include other portions that mate with the heated-fluid generator device **200**. In this embodiment, the connector **500** includes a circumferential seal **530** proximal to an intermediate stab portion **535**. The intermediate stab portion is configured to fit within a mating sealing surface **235** of the heated-fluid generator device **200** when the previously described threads **440** are used to secure the connector **500** to the heated-fluid generator device **200**. In such circumstances, the seal **530** may substantially seal against the mating sealing surface **235** to prevent seepage of fluid between the ports **560** and **570** of the

connector 500 (see FIG. 3). The connector may also include a circumferential seal 540 disposed proximal to an inner stab portion 545. The inner stab portion is configured to fit within a mating receptacle 245 of the heated-fluid generator device 200 when the connector 500 is secured to the heated-fluid generator device 200. The intermediate stab portion 535 and the inner stab portion 545 may be a press fit connection or some other type of mechanical connection.

In this embodiment, the connector 500 is configured to be at least partially received in the polished bore receptacle 450 of the liner hanger 400. For example, the connector 500 may include at least one locating shoulder 550 (sometimes referred to as a no-go shoulder). The locating shoulder 550 may be configured to rest upon a mating shoulder 452 of the polished bore receptacle 450. As such, the shape of the polished bore receptacle 450 may centralize the position of the connector 500 as the device 500 is lowered into the liner hanger 400. As previously described, the circumferential seal 510 of the self centralizing connector 500 substantially seals against the polished inner wall of the polished bore receptacle 450 to prevent fluid in the outer conduit 115 from seeping past the threads 440.

Referring now to FIG. 3, the ports 560, 570, and 580 guide supply fluids to the appropriate inputs of the heated-fluid generator device 200. Accordingly, the ports 560, 570, 580 are positioned on the connector 500 to communicate with their respective conduits 115, 615, 715. The ports 560, 570, 580, in turn, are provided in communication with a respective port of the heated-fluid generator device 200 (see FIG. 2). Each of ports 560, 570, and 580 can be a single aperture or multiple apertures as is shown in FIG. 3. Furthermore, the ports need not be circular as is depicted in FIG. 3, but may be other shapes.

In some embodiments, the outer ports 560 may feed a fluid from the outer conduit 115 to the input of the heated-fluid generator device 200. Also, the intermediate ports 570 may feed another fluid from the intermediate conduit 615 to the input of the heated-fluid generator device 200. Furthermore, the inner port 580 may feed a third fluid from the inner conduit 715 to the input of the heated-fluid generator device 200. In one instance, the heated-fluid generator device 200 is a steam generator, the outer conduit 115 can contain water, the intermediate conduit 615 air, and the inner conduit 715 fuel (e.g. natural gas). In other instances where the heated-fluid generator device 200 is a steam generator, depending on the specifics of the application, the outer conduit 115 can contain air or fuel, the intermediate conduit 615 water or fuel, and the inner conduit 715 water or air.

In operation, the supply tube system 140 and the heated-fluid generator device 200 may be deployed into the wellbore 160 separately or partially assembled. Referring to FIG. 4, one exemplary method 800 of coupling a heated-fluid generator device 200 to a supply tube system 140 may include deploying at least one tube within another tube. The method 800 may include an operation 805 of assembling the connector 500 to the heated-fluid generator device 200. For example, the connector 500 may be secured to the heated-fluid generator device 200 using the threads 440 (FIG. 2) or other previously described connections. The method 800 may also include the operation 810 of assembling the intermediate tubing 610 to the connector 500. The intermediate tubing 610 may be assembled to the connector using threads 622 or another mechanical engagement device.

After the intermediate tube 610 and the heated-fluid generator device 200 are coupled to one another via the connector 500, the method 800 may further include the operation 815 of lowering the intermediate tube 610 and the heated-fluid gen-

erator device 200 into the wellbore 160. As previously described, the intermediate tube 610 may comprise a continuous metallic tubing that is uncoiled at the surface 150 as the intermediate tube is lowered into the wellbore 160. In such instances, the continuous metallic tubing may be plastically deformed from a coiled state to an uncoiled state (e.g., generally straightened or the like) as the intermediate tube is lowered into the wellbore 160. The wall thickness and material properties of the intermediate tube 610 may provide sufficient strength to support at least a portion of the weight of the heated-fluid generator device as it is lowered into the wellbore.

When heated-fluid generator device 200 is lowered to a position proximal to the formation 130, the method may include the operation 820 of aligning and coupling the heated-fluid generator device 200 to the liner hanger 400. For example, the heated-fluid generator device 200 may be aligned with and couple to the liner hanger 400 when the shoulder 550 of the connector 500 engages the polished bore receptacle 450 in the liner hanger 400. In some circumstances, the method 800 may also include the operation 825 of spacing out, landing, and packing off the intermediate tube 610 proximal to the ground surface 150. Such an operation may facilitate the deployment of the inner tube 710 from the ground surface 150 and through the intermediate tube 610.

The method 800 may further include the operation 830 of lowering the inner tube 710 into the wellbore 160 inside the intermediate tubing 610. As previously described, the inner tube 710 may comprise continuous metallic tubing having a smaller diameter than that of the intermediate tube 610 (refer, for example, to FIG. 1 which shows the spool 145 of continuous tubing that is uncoiled as it is lowered into the wellbore 160). In some embodiments, the inner tube 710 may include the stinger/seal assembly 720 disposed at the lower end thereof so that the inner tube 710 can join with the connector 500 located downhole.

When the inner tube 710 reaches the appropriate depth, the method 800 may include the operation 835 of coupling the inner tube 710 to the heated-fluid generator device 200. In some embodiments, the inner tube 710 may be coupled to the heated-fluid generator device 200 when the stinger/seal assembly 720 engages the connector 500 and the latch mechanism 730 engages the mating groove 524. As such, the wall of the inner tube 710 may separate the inner conduit 715 from the intermediate conduit 615.

The method 800 may also be used to supply fluids to the downhole heated-fluid generator device 200. As shown in operation 840, fluids (e.g., water, air, and fuel such as natural gas) may be supplied separately into an associated conduit 115, 615, and 715. For example, natural gas may be supplied through the inner conduit 715, air or oxygen gas may be supplied through the intermediate conduit 615, and water may be supplied through the casing conduit 115. The method 800 may also include the operation 845 of feeding the fluids (e.g., water, air, and fuel such as natural gas) inside the conduits 715, 615, 115 of the supply tube system 140 into the heated-fluid generator device 200. For example, the air and natural gas may be used in a combustion process or a catalytic process, which heats the water into steam. The method 800 may also include the operation 850 of applying the heated fluids (e.g., steam) to at least a portion of the formation 130. As previously described, the heated-fluid generator device 200 may be disposed in the wellbore so that the exhaust port 210 is proximal to the formation 130. When the water is converted into steam by the downhole heated-fluid generator device 200, the steam may be applied to the formation 130 as it is output from the port 210.

It should be understood that the supply tube system 140 and the heated-fluid generator device 200 may be coupled and lowered into the wellbore 160 using methods other than those described in FIG. 4. In one example, the inner tube 710 and the intermediate tube 610 may be coupled with the heated-fluid generator device 200 using the connector 500 above the ground surface. Then the inner tube 710, the intermediate tube 610, connector 500, and heated-fluid generator device 200 may be simultaneously lowered into the wellbore 160 until the connector 500 engages the polished bore receptacle 450 in the liner hanger 400. In another example, the inner tube 710 and the intermediate tube 610 may not be coupled with the heated-fluid generator device 200 using the connector 500 above the ground surface. Instead, the heated-fluid generator device 200 and the connector 500 may be disposed downhole within the liner hanger 400 before the tubes 610 and 710 are lowered thereto. The intermediate tube 610 and the inner tube 710 may use threaded connections or stab connections to engage the connector 500. In yet another example, the intermediate tube 610 may be coupled with the connector 500 above the ground surface and then lowered into the well to engage the heated-fluid generator device 200 located in the wellbore 160. In such circumstances, the inner tube 710 may be lowered into the wellbore 160 inside the intermediate tube 610 until the stinger/seal assembly 720 attached to the end of the inner tube 710 engages the connector 500.

A number of embodiments of the invention have been described. Nevertheless, it will be understood that various modifications may be made without departing from the spirit and scope of the invention. Accordingly, other embodiments are within the scope of the following claims.

What is claimed is:

1. A method, comprising:

lowering a heated-fluid generator device into a wellbore while the heated-fluid generator device is coupled to a first tube, wherein the heated-fluid generator device comprises a steam generator to output steam to a region proximal to the wellbore; and coupling a second tube to the heated-fluid generator, at least one of the first tube and the second tube comprising a coiled tubing uncoiled from a spool and inserted into the wellbore, wherein at least one of the first tube and the second tube at least partially defines an annular conduit to deliver water to a water input port of the steam generator.

2. The method of claim 1, wherein the first tube supports at least a portion of a weight of the heated-fluid generator device while lowering the heated-fluid generator device into the wellbore.

3. The method of claim 1, wherein one of the first and second tubes is disposed inside of the other tube to define a first fluid conduit inside of a second fluid conduit.

4. The method of claim 1, further comprising coupling the first tube to the heated-fluid generator device using a connector, wherein one of the connector and the second tube comprises a stab portion and the other comprises a receptacle adapted to sealingly receive the stab portion and couple second tube with the connector after the heated-fluid generator device is lowered into the wellbore.

5. The method of claim 4, wherein the connector comprises a first port in communication with the first fluid conduit and the heated-fluid generator device and comprises a second port in communication with the second conduit and the heated-fluid generator device.

6. The method of claim 1, wherein the first tube and the second tube are received within a casing and the casing, the

first tube, and the second tube at least partially define at least three substantially nested conduits.

7. The method of claim 6, further comprising receiving a fuel through the first conduit to the heated-fluid generator device, receiving an oxygen-containing fluid through the second conduit to the heated-fluid generator device, and receiving water through a third conduit.

8. The method of claim 1, further comprising delivering water, an oxygen-containing fluid, and a fuel at the heated-fluid generator device so as to apply a heated fluid to a hydrocarbon formation disposed proximal to the wellbore.

9. The method of claim 1, wherein at least one of the first tube and the second tube is continuous between the heated-fluid generator and a ground surface.

10. A method, comprising:

lowering a heated-fluid generator device into a wellbore while the heated-fluid generator device is coupled to a first tube, the first tube being uncoiled from a spool as the heated-fluid generator device is lowered into the wellbore, wherein the heated-fluid generator device comprises a steam generator to output steam to a region proximal to the wellbore;

securing the heated-fluid generator device in a polished bore receptacle so as to form a seal therebetween, wherein an output port of the steam generator is arranged below the seal; and

coupling a second tube to the heated-fluid generator, one of the first and second tubes nested within the other to define at least a portion of at least two fluid conduits.

11. The method of claim 10, wherein the first tube supports at least a portion of a weight of the heated-fluid generator device while it is being lowered into the wellbore.

12. The method of claim 10, wherein the first tube and the second tube define at least a portion of at least three fluid conduits.

13. The method of claim 10, wherein the first tube is substantially continuous between the heated-fluid generator device and a ground surface.

14. The method of claim 10, wherein lowering the heated-fluid generator device into a wellbore further comprises receiving the heated-fluid generator device at a liner hanger having the polished bore receptacle.

15. A system for generating heated fluid in a wellbore, comprising:

a heated-fluid generator device disposed in a wellbore and adapted to output a heated fluid, wherein the heated-fluid generator device comprises a steam generator; and a first and second tubes residing in the wellbore and coupled to the heated-fluid generator, the first tube at least partially defining a first conduit and the second tube at least partially defining a second conduit, both the first and second conduits being in fluid communication with the heated-fluid generator device, wherein at least one of the first and second tubes comprises a coiled tubing that is uncoiled from a spool when arranged in the wellbore; and

a wellbore casing disposed in the wellbore, the wellbore casing surrounding at least a portion of the second tube to define a third conduit between the casing and the second tube, the third conduit adapted to communicate a fluid into an input of the heated-fluid generator device.

16. The system of claim 15, wherein the first tube resides within the second tube so as to define an inner fluid conduit disposed within an intermediate fluid conduit.

17. The system of claim 15, wherein at least one of the first and second tubes is substantially continuous between the heated-fluid generator and a ground surface.

11

18. The system of claim 15, further comprising:
a hanger device adapted to grip a wall of the wellbore and
adapted to receive and support the heated-fluid generator
device in the wellbore; and
a connector adapted to couple at least one of the first and
second tubes to the heated-fluid generator device and
adapted to substantially seal against the hanger device.

19. A method, comprising:

lowering a heated-fluid generator device into a wellbore
while the heated-fluid generator device is coupled to a
first tube; and

coupling a second tube to the heated-fluid generator, at
least one of the first tube and the second tube comprising
a coiled tubing uncoiled from a spool and inserted into
the wellbore,

wherein the first tube is coupled to the heated-fluid genera-
tor device using a connector, and one of the connector
and the second tube comprises a stab portion and the
other comprises a receptacle adapted to sealingly receive
the stab portion and couple second tube with the
connector after the heated-fluid generator device is lowered
into the wellbore.

20. The method of claim 19, wherein the first tube supports
at least a portion of a weight of the heated-fluid generator
device while lowering the heated-fluid generator device into
the wellbore.

21. The method of claim 19, wherein one of the first and
second tubes is disposed inside of the other tube to define a
first fluid conduit inside of a second fluid conduit.

22. The method of claim 19, wherein the connector com-
prises a first port in communication with the first fluid conduit
and the heated-fluid generator device and comprises a second
port in communication with the second conduit and the
heated-fluid generator device.

23. The method of claim 19, wherein the first tube and the
second tube are received within a casing and the casing, the
first tube, and the second tube at least partially define at least
three substantially nested conduits.

24. The method of claim 23, further comprising receiving
a fuel through the first conduit to the heated-fluid generator
device, receiving an oxygen-containing fluid through the sec-
ond conduit to the heated-fluid generator device, and receiv-
ing water through a third conduit.

25. The method of claim 19, wherein the heated-fluid gen-
erator device comprises a steam generator, the method further
comprising delivering water, an oxygen-containing fluid, and
a fuel to the heated-fluid generator device so as to apply a
heated fluid to a hydrocarbon formation disposed proximal to
the wellbore.

26. The method of claim 19, wherein at least one of the first
tube and the second tube is continuous between the heated-
fluid generator and a ground surface.

27. The method of claim 19, wherein lowering the heated-
fluid generator device into a wellbore further comprises
receiving the heated-fluid generator device at a liner hanger.

28. The method of claim 27, wherein receiving the heated-
fluid generator device at the liner hanger further comprises
sealingly coupling the heated-fluid generator device to a pol-
ished bore receptacle of the liner hanger.

29. A method, comprising:

lowering a heated-fluid generator device into a wellbore
while the heated-fluid generator device is coupled to a
first tube, wherein lowering the heated-fluid generator
device into a wellbore further comprises receiving the
heated-fluid generator device at a liner hanger; and

12

coupling a second tube to the heated-fluid generator, at
least one of the first tube and the second tube comprising
a coiled tubing uncoiled from a spool and inserted into
the wellbore.

30. The method of claim 29, wherein the first tube supports
at least a portion of a weight of the heated-fluid generator
device while lowering the heated-fluid generator device into
the wellbore.

31. The method of claim 29, wherein one of the first and
second tubes is disposed inside of the other tube to define a
first fluid conduit inside of a second fluid conduit.

32. The method of claim 29, further comprising coupling
the first tube to the heated-fluid generator device using a
connector, wherein one of the connector and the second tube
comprises a stab portion and the other comprises a receptacle
adapted to sealingly receive the stab portion and couple sec-
ond tube with the connector after the heated-fluid generator
device is lowered into the wellbore.

33. The method of claim 32, wherein the connector com-
prises a first port in communication with the first fluid conduit
and the heated-fluid generator device and comprises a second
port in communication with the second conduit and the
heated-fluid generator device.

34. The method of claim 29, wherein the first tube and the
second tube are received within a casing and the casing, the
first tube, and the second tube at least partially define at least
three substantially nested conduits.

35. The method of claim 34, further comprising receiving
a fuel through the first conduit to the heated-fluid generator
device, receiving an oxygen-containing fluid through the sec-
ond conduit to the heated-fluid generator device, and receiv-
ing water through a third conduit.

36. The method of claim 29, wherein the heated-fluid gen-
erator device comprises a steam generator, the method further
comprising delivering water, an oxygen-containing fluid, and
a fuel to the heated-fluid generator device so as to apply a
heated fluid to a hydrocarbon formation disposed proximal to
the wellbore.

37. The method of claim 29, wherein at least one of the first
tube and the second tube is continuous between the heated-
fluid generator and a ground surface.

38. The method of claim 29, wherein receiving the heated-
fluid generator device at the liner hanger further comprises
sealingly coupling the heated-fluid generator device to a pol-
ished bore receptacle of the liner hanger.

39. A method, comprising:
lowering a heated-fluid generator device into a wellbore
while the heated-fluid generator device is coupled to a
first tube, the first tube being uncoiled from a spool as the
heated-fluid generator device is lowered into the well-
bore, wherein lowering the heated-fluid generator
device into a wellbore further comprises receiving the
heated-fluid generator device at a liner hanger; and
coupling a second tube to the heated-fluid generator, one of
the first and second tubes nested within the other to
define at least a portion of at least two fluid conduits.

40. The method of claim 39, wherein the first tube supports
at least a portion of a weight of the heated-fluid generator
device while it is being lowered into the wellbore.

41. The method of claim 39, wherein the first tube and the
second tube define at least a portion of at least three fluid
conduits.

42. The method of claim 39, wherein the first tube is sub-
stantially continuous between the heated-fluid generator
device and a ground surface.

43. The method of claim 39, wherein receiving the heated-
fluid generator device at the liner hanger further comprises

13

sealingly coupling the heated-fluid generator device to a polished bore receptacle of the liner hanger.

44. A system for generating heated fluid in a wellbore, comprising:

- a heated-fluid generator device disposed in a wellbore and adapted to output a heated fluid;
- a first and second tubes residing in the wellbore and coupled to the heated-fluid generator, the first tube at least partially defining a first conduit and the second tube at least partially defining a second conduit, both the first and second conduits being in fluid communication with the heated-fluid generator device, wherein at least one of the first and second tubes comprises a coiled tubing that is uncoiled from a spool when arranged in the wellbore;
- a hanger device adapted to grip a wall of the wellbore and adapted to receive and support the heated-fluid generator device in the wellbore; and

14

a connector adapted to couple at least one of the first and second tubes to the heated-fluid generator device and adapted to substantially seal against the hanger device.

45. The system of claim **44**, wherein the first tube resides within the second tube so as to define an inner fluid conduit disposed within an intermediate fluid conduit.

46. The system of claim **45**, further comprising a wellbore casing disposed in the wellbore, the wellbore casing surrounding at least a portion of the second tube to define a fluid conduit between the casing and the second tube.

47. The system of claim **44**, wherein at least one of the first and second tubes is substantially continuous between the heated-fluid generator and a ground surface.

48. The system of claim **44**, wherein the heated-fluid generator device comprises a steam generator.
